METHOD OF DRILLING WELLS

Harold L. Woods, Monroe, La.

No Drawing. Application June 6, 1934,
Serial No. 729,343

6 Claims. (Cl. 255—1)

This invention relates in general to improvements in drilling wells, and particularly to a method adapted to prevent sealing off of the porous producing strata by the mud-bearing fluid ordinarily used during drilling.

It is the object of this invention to increase the flow and yield from a well by preventing porous strata containing oil, gas, or water from being penetrated and clogged by drill muds.

It is another object of this invention to constantly open up the pay strata containing oil, gas, or water while they are being drilled as distinguished from the usual sealing action which ordinary drill fluids produce in such porous strata.

It is the further object of this invention to drill a bore hole which will be in a condition to produce oil, gas, or water as the case may be immediately at the conclusion of the drilling operation and without any necessity for cleaning or dissolving colloidal drill mud out of the pores of the producing strata.

With the present methods of drilling wells by the use of a rotary cutter, it is customary to pump a drill mud downward through the drill stem while drilling. The drill mud picks up the earth cuttings and conveys them to the surface as it circulates upwardly between the drill stem and the bore hole casing.

Ordinary drill mud consists of finely divided clays and similar matter suspended in a liquid to form a slush of the desired viscosity. The drill mud at the lower end of the bore hole being drilled is under considerable pressure due to the weight of the column of fluid above. This pressure normally causes the drill mud to penetrate laterally into the porous strata encountered in drilling and to seal off these strata by closing or clogging the pores existing therein.

The producing strata are generally of a porous nature and suffer considerable damage when drilled with conventional drill mud. It is both difficult and expensive to remove the drill mud from the porous pay strata once it has penetrated into the same. To avoid this damage, it has been heretofore proposed to treat the drill muds chemically to lessen their degree of penetration into porous strata. It has also been proposed to treat the bore hole with chemicals after it has been drilled in order to clean out as far as possible drill mud which has clogged the pay strata. In this connection, acids have been used to clean out the colloidal drill muds which have penetrated into and clogged up the porous formations during drilling and to enlarge the cavities in such formations.

In the improved method of drilling according to the present invention, it has been found that the damage and injury which ordinary or treated drill muds do to porous strata may be economically avoided by the substitution of other circulating mediums than drill mud when the bore hole reaches an oil, gas, or water bearing strata. It has been found that greatly improved results can be obtained by the use of a suitable acid solution as the drill fluid while drilling such strata, or in general by the use of a fluid adapted to disintegrate the material of which such strata are composed instead of sealing off the same.

The invention contemplates the use of any suitable acid, such as commercial hydrochloric, nitric or sulphuric acid, or mixtures thereof, for example, in drilling operations where the producing stratum consists of lime or calcareous formation. The acid or acids used may be of any suitable concentration and may have an inhibiting agent, such as 1 to 10% of a soluble arsenic compound, mixed therewith to minimize corrosive action on the well casing, drill stem, and like apparatus with which the drill fluid comes in contact.

The practice of this invention will now be described in connection with a specific example of drilling. In the Many-Zwolle field in Sabine Parish, Louisiana, a well is drilled to a depth of twenty-three hundred feet by the use of ordinary drill mud and drilling apparatus. At this level the top of a lime, chalk, or marl formation is reached. A casing is set and cemented and the ordinary drill mud is removed from the well. The rotary drill stem is returned to the bore hole which is then filled with a suitable inhibited acid solution, for example, a 5-25% hydrochloric acid solution. As the drilling then progresses through the porous pay formation, the acid circulating fluid acts immediately on this stratum and increases the size of the pores and the cavities therein. As there is no drill mud present at this level, the porous formation never is penetrated or clogged by colloidal muds but is constantly cleaned and opened by the action of the acid circulating fluid. After the drilling operation is completed, the well is immediately ready for producing.

As the acid drill fluid is used only while drilling the porous pay strata, the acid is used where it can produce the greatest possible amount of benefit and it is not lost or consumed by leakage into non-pay formations. If the acid were used for a circulating fluid during the drilling of the entire well, the losses would be so great that the cost of the acid would be prohibitive. Where the

bore is treated with acids after drilling, the acids are often lost through the most porous part of the strata, the other sections of the porous strata remaining untreated. Also the subsequent treatment with acid after the stratum has been sealed off, does not produce results comparable with these obtained by the process described. Confining the use of the acid to the drilling of the porous pay strata enables the acid to be used most effectively and economically.

Although it is preferred to circulate the acid solution downwardly in the drill stem and upwardly between the stem and casing as in the case of conventional drilling, it is also possible to achieve the desirable results of this invention by allowing the acids merely to stand in the bore hole during a part or the entire period that the porous pay strata is being drilled.

From the above description it will be apparent that by the use of this improved method of drilling through porous strata in the presence of acids, the bore hole will be in its best possible producing condition when drilling has reached the desired level; that it will be unnecessary to undertake subsequent cleaning operations to remove muds from the porous strata; and that much better results are possible than those obtained merely by subsequent attempts to clean the pay strata after the drilling has been completed.

30 I claim:

1. In well drilling operations, the method of opening the pores of porous producing formations, which comprises removing the mud circulating fluid upon reaching said formation, introducing an acid solution into the well and conducting the drilling operation in the producing formation in the presence of said acid solution.

2. In well drilling operations, the method comprising drilling the initial portion of the well in the presence of a mud circulating fluid, removing the mud circulating fluid, substituting an acid

solution therefor, and then drilling that portion of the well which traverses porous producing strata while circulating therein the said acid solution.

3. In well drilling operations, the method of protecting porous producing strata from being damaged by drill muds, which comprises drilling the initial non-porous portion of the well in the presence of a mud fluid, then removing the mud fluid from the well, introducing an acid into the well, and drilling said porous strata in the presence of said acid.

4. In well drilling operations, the method comprising initially drilling in the well while circulating mud fluid through the boring until a producing stratum is reached, then removing said mud fluid and introducing into the well a fluid having the chemical property of disintegrating the material of which said stratum is composed, and continuing with the drilling in said stratum in the presence of the said disintegrating fluid.

5. In well drilling operations, the method comprising circulating mud fluid through the boring during the initial drilling and until a calcerous producing stratum is reached, then replacing the mud fluid with hydrochloric acid and continuing the drilling while circulating the hydrochloric acid through the boring.

6. In well drilling operations, the method comprising drilling the initial part of the well and to a depth which extends through the non-producing strata in the presence of a mud circulating fluid, then removing said mud fluid from the boring, substituting therefor an acid solution containing hydrochloric acid of from 5 to 25% concentration together with a corrosion inhibitor of concentration of 1 to 10%, and drilling that part of the well which traverses calcerous producing stratum while circulating said acid solution therein.

CERTIFICATE OF CORRECTION.

Patent No. 2,030,777.

HAROLD L. WOODS.

It is hereby certified that error appears in the printed specification of the above numbered patent requiring correction as follows: Page 1, second column, line 11-12, for "distintegrate" read disintegrate; same page and column, line 14, for "The" read This; page 2, second column, lines 24 and 38 claims 5 and 6 respectively, for "calcerous" read calcareous; and that the said Letters Patent should be read with these corrections therein that the same may conform to the record of the case in the Patent Office.

Signed and sealed this 3rd day of March, A. D. 1936.

(Seal)

Leslie Frazer
Acting Commissioner of Patents.
